REFLECTOR LIGHT HOUSING

Walter T. Cox, Royal Oak, Mich., assignor to Theodore Bargman Company, Detroit, Mich., a corporation of Michigan

Filed Feb. 3, 1969, Ser. No. 15,611

Term of patent 14 years

Int. Cl. D12—99; D29—99

U.S. Cl. D48—32

FIG. 1 is a plan view of a reflector light housing showing my new design.

FIG. 2 is a side elevational view thereof, the opposite side being the same.

FIG. 3 is an end elevational view thereof, the opposite side being the same.

FIG. 4 is a sectional view along the line 4—4 in FIG. 1.

FIG. 5 is a sectional view along the line 5—5 in FIG. 1.

FIG. 6 is a fragmentary sectional view on an enlarged scale taken on line 6—6 of FIG. 4.

FIG. 7 is a fragmentary sectional view on an enlarged scale taken on line 7—7 of FIG. 4.

The bottom of the light housing is plain.

I claim:

The new and ornamental design for a reflector light housing, substantially as shown and described.
